His ATTORNEY.

UNITED STATES PATENT OFFICE.

RUDOLPH HIRSCH, OF KANSAS CITY, MISSOURI.

MEASURING-COVER FOR CANS.

No. 928,052.

Specification of Letters Patent.

Patented July 13, 1909.

Application filed May 15, 1908. Serial No. 433,101.

To all whom it may concern:

Be it known that I, RUDOLPH HIRSCH, a citizen of the United States, residing at Kansas City, in the county of Jackson and State of Missouri, have invented certain new and useful Improvements in Measuring-Covers for Cans, of which the following is a specification.

My invention relates to improvements in 10 measuring covers for cans.

It is particularly adapted for use in connection with cans containing baking powder or similar substances.

The object of my invention is to provide a 15 cover by which the contents of the can may be delivered therefrom in accurately measured portions.

A further object of my invention is to provide a cover which need not be removed when 20 material is being taken from the can, which is sanitary in operation and by which moisture and dirt are excluded from the can.

The novel features of my invention are hereinafter fully described and claimed.

25 In the accompanying drawings illustrative of my invention—Figure 1 is a perspective view showing my improved measuring cover mounted on the top of a can. Fig. 2 is a central vertical sectional view of what is shown in Fig. 1, the lower closure being shown in the open position and the upper closure in the closed position. Fig. 3 is a plain view, a portion of the upper closure being broken away. Fig. 4 is a horizontal sectional view taken on 30 the dotted line *a*—*b* of Fig. 2. Fig. 5 is a vertical sectional view of the measuring cover taken on the dotted line *c*—*d* of Fig. 3, the upper closure being shown in the open position and the lower closure in the closed 35 position.

Similar characters of reference denote similar parts.

1 denotes an ordinary cylindrical open top can, the open end of which is adapted to be 40 closed by my improved measuring cover.

The measuring cover comprises an inverted cup-shaped member or cover 2 into the lower open end of which the upper end of the can 1 is adapted to be inserted. The 45 cover 2 is provided with a horizontal partition 3 disposed above and closing the upper end of the can 1. A vertical measuring tube 4, preferably of conical form, extends through the partition 3 and the horizontal 50 top of the cover 2. The ends of the measuring tube 4 are preferably provided with

annular flanges 5, secured respectively to the upper side of the cover 2 and the lower side of the partition 3. An inverted cup-shaped cap 6 is fitted over the cover 2 for closing the 60 upper end of the tube 4. The vertical wall of the cover 6 is provided with an annular, inwardly extending projection 7, fitted in an annular peripheral groove 8, provided in the vertical wall of the cover 2. The projection 65 7 secures the cap 6 in its proper position and permits rotation of the cap upon the cover. The cover is secured at its center to the upper end of a vertical shaft 9, which extends through and is rotatively mounted in the 70 partition 3 and horizontal portion of the cover 2. Secured to the lower end of the shaft 9 below the partition 3 is a closure for the lower end of the tube 4, comprising 75 preferably a horizontal disk 10, provided with a vertical opening 11, adapted to register with the lower end of the tube 4. A similar opening 12 is provided in the horizontal portion of the cap 6 and is adapted to register with the upper end of the tube 4. 80 The relative disposition of the openings 11 and 12 is such that both openings cannot at the same time be in register with the tube 4. As shown in the drawings these openings are disposed preferably at diametrically opposite sides of the shaft 9. For holding the cap 6 releasably in both closed and open positions the said cap is provided in its vertical wall with an inwardly extending projection 14 adapted to consecutively enter two in- 85 indentations or recesses 13 disposed at diametrically opposite points in the vertical wall of the cover 2. The disposition of the recesses 13 and projection 14 is such that the cap 6 will be releasably locked to the 90 cover 2 in the open position shown in Fig. 5, and the closed position shown in Fig. 2.

In the operation of my invention, the can 1 is inverted, the cap 6 first having been rotated to the position shown in Fig. 2, in which 100 position the opening 11 in the disk 11 will register with the tube 4, and the cap 6 will close the upper end of said tube. The can being inverted the material therein will fill the tube 4. The cap 6 is then rotated to the position 105 shown in Fig. 5 in which position the disk 10 will close the lower end of the tube and the opening 12 will register with the tube 4. The outlet of the tube 4 being open the material held in said tube will be discharged 110 therefrom. The capacity of the tube 4 may be a tea spoonful, a table spoonful or such

other unit of measurement as may be desired. If more than one charge of the tube 4 is required, the cap 6 is rotated 180 degrees, thus placing the opening 11 again in register with the tube 4, thereby permitting another charge to enter the tube from the can. The cap is then rotated another 180 degrees, thus placing the opening 12 in register with the tube 4, so as to discharge the contents therefrom. In like manner the cap 6 may be rotated to obtain as many charges as is desired. When the required quantity has been removed from the can the cap 6 is rotated to the position shown in Fig. 2, thus closing the outlet of the tube 4 and preventing access therein and to the can of dirt or moisture.

My invention may be modified in different ways, within the scope of the appended claims, without departing from its spirit.

Having thus described my invention, what I claim and desire to secure by Letters Patent, is:—

1. A measuring cover for can tops comprising an inverted cup shaped cover adapted to have its open end fitted to a can top and provided with a transverse horizontal partition, a vertical measuring tube extending through the cover top and said partition, a cap pivoted to said cover for closing the upper end of said tube, said cap being rotatively mounted on the cover and provided with a discharge opening disposed so as to register with the opening through the tube when the cap is rotated to the proper position on the cover, and a horizontal disk disposed below the partition for closing the lower end of said tube, said disk being rotatable with said cap and provided with a vertical opening disposed in position to register with said tube when the cap is disposed in the proper position, the relative disposition of the openings in the cap and disk being such that they can not both be in register with the tube at the same time.

2. In a measuring cover for can tops, the combination with a cup shaped cover, having a horizontal partition disposed above the lower edge of the cover, of a measuring tube extending through the top of said cover and through said partition, a cap rotatively mounted on said cover for closing the upper end of said tube and having a vertical opening adapted to register with said tube, and means carried by said cover and rotatable therewith for closing the lower end of said tube when the cap is in a position in which the opening in the cap is in register with said tube.

3. In a measuring cover for can tops, the combination with a cup shaped cover adapted to have its open lower end fitted over a can top, of a vertical measuring tube extending through the top of the cover, a vertical shaft rotatively mounted in the top of said cover, and means carried by said shaft for

alternately closing the upper and lower ends of said tube when the shaft is rotated.

4. In a measuring cover for can tops, the combination with a cup shaped cover adapted to have its open end fitted over a can top, of a vertical measuring tube extending through and secured to the top of the cover, and means for alternately closing the upper and lower ends of said tube.

5. In a measuring cover, the combination with a cup shaped cover adapted to have its open end fitted over a can top, and provided above its lower edge with a horizontal partition, a measuring tube extending through said partition and the top of said cover, and means for alternately closing the upper and lower ends of said tube.

6. In a measuring cover the combination with a cup shaped cover adapted to have its open end fitted over a can top, and having a horizontal partition above its lower edge, of a tube extending through said partition and the top of said cover, two closures rotatively mounted on said cover for alternately closing the upper and lower ends of said tube, releasable yielding means provided on the cover for holding said closures in the closed positions and means connecting the two closures.

7. In a measuring cover, the combination with a cup shaped cover adapted to have its open end fitted over a can top, and having a horizontal partition above its lower edge, of a tube extending through said partition and the top of said cover, two closures rotatively mounted on said cover for alternately closing the upper and lower ends of said tube and means connecting the two closures.

8. In a measuring cover, the combination with a cup shaped cover adapted to have its open end fitted over a can top, and having a horizontal partition above its lower edge, and provided with an annular peripheral groove, of a measuring tube extending through said partition and the top of said cover, a cup shaped cap fitted over said cover for closing said tube at its upper end and having an opening adapted to register with said tube, the cap having an annular inwardly extending peripheral projection fitted in said groove, a vertical shaft extending through said partition and said cover and secured to said cap, and means carried by said shaft for closing the lower end of said tube when the opening in the cap is in register with said tube.

9. In a measuring cover, the combination with a cup shaped cover adapted to be fitted over a can top, and provided above its lower edge with a horizontal partition, of a measuring tube extending through said cover and said partition, a cup shaped cap rotatively fitted on said cover for closing the upper end of said tube and having an opening adapted to register with said tube, means

carried by the cap for closing the lower end of said tube when the opening in the cap is in register with said tube, and releasable yielding means provided on the cover for holding said cap in closed and open position.

10. In a measuring cover, the combination with a cup shaped cover adapted to be fitted to the top of a can, and having a horizontal partition, of a measuring tube extending through said partition and the top of said cover, a cup shaped cap rotatively mounted on said cover and provided in its top with an opening adapted to register with said tube, the cap at other positions thereof closing the upper end of said tube, releasable yielding means provided on the cover for holding said cap in the open and closed positions, a shaft extending through and rotatively mounted in said partition and the top of said cover and secured at its upper end to said cap, and a closure secured to the lower end of said shaft for closing the lower end of said tube when the opening in the cap is in register with said tube.

25 11. In a measuring cover, the combination with a cup shaped cover adapted to be fitted to the top of a can and having a horizontal partition, a vertical shaft extending through and rotatively mounted in said partition and the top of said cover, a measuring tube extending through said partition and the top of said cover, a cup shaped cap for closing the upper end of said tube rotatively mounted on said cover and provided with a vertical opening adapted to register with said tube, the cap being secured to the said shaft, and a horizontal disk secured to the lower end of said shaft for closing the lower end of said tube and provided with a vertical opening adapted to register with said tube, the disposition relatively of the openings in the cap and disk being such that both openings will not register with the tube at the same time.

12. In a measuring cover, the combination with a cup shaped cover adapted to be fitted to a can top and having a peripheral annular groove in its side wall, and having a horizontal partition, of a cup shaped cap fitted rotatively upon said cover and having in its side wall an annular projection fitted in said groove, and provided in its top with a vertical opening, a tube extending through the partition and top of said cover and adapted to have its upper end register with said opening, a vertical shaft extending through and rotatively mounted in said partition and the top of said cover and secured to said cap, and a horizontal disk secured to the lower end of said shaft for closing the lower end of said tube, and having a vertical opening adapted to register with said tube, the openings in the cap and disk being so disposed that both openings can not at the same time register with said tube.

65 13. The combination with a can having an

open upper end, of a cup shaped cover fitted over said open end of the can and provided with a horizontal partition disposed above the upper end of the can, a vertical measuring tube extending through the top of said cover and said partition, two closures rotatively mounted on said cover for alternately closing the upper and lower ends of said tube and means connecting the two closures.

14. The combination with a can having an open upper end, of a cup shaped cover fitted over said open end and provided with a horizontal partition, a vertical measuring tube extending through said partition and the top of said cover, a rotary shaft extending through said partition and cover, and two closures secured to said shaft and disposed so as to alternately close the upper and lower ends of said tube.

15. The combination with a can having an open upper end, of a cup shaped cover fitted to said open end and having a horizontal partition, a vertical measuring tube extending through said partition and the top of said cover, a cup shaped cap encircling said cover and adapted to close the upper end of said tube, and having an opening adapted to register with said tube, a shaft secured to said cap and extending through said cover and partition, and a closure secured to said shaft below said partition for closing the lower end of said tube, the relative disposition of said closure and said opening being such that when the opening is in register with said tube the closure will cover the lower end of said tube.

16. The combination with a can having an open upper end, of a cup shaped cover fitted to said open end and having a horizontal partition closing the upper end of the can, a measuring tube extending through said partition and the top of said cover, a cup shaped cap fitted over said cover for closing the upper end of said tube and having an opening adapted to register with said tube, and provided with an inwardly projecting annular projection on its vertical wall, the cover having an annular groove in which said annular projection is fitted, a rotary shaft extending through said partition and cover and to which the cap is secured and rotatable therewith, and a closure secured to the lower end of said shaft below said partition for closing the lower end of said tube, said closure and said opening in the cap being disposed relatively in positions in which the closure will cover the lower end of the tube when the opening registers with the tube.

In testimony whereof I have signed my name to this specification in presence of two subscribing witnesses.

RUDOLPH HIRSCH.
